Automated Parcel Terminals—The Best Solution For Logistics Companies, <https://parcelhive.net/logistics-companies-terminals/>, copyright 2020. (Year: 2020).*

Primary Examiner — Elizabeth J Oswecki(74) *Attorney, Agent, or Firm* — Meunier Carlin & Curfman LLC**CLAIM**

The automated parcel terminal, as shown and described.

DESCRIPTION

FIG. 1 is a top, isometric view of an automated parcel terminal, showing my new design;

FIG. 2 is a bottom, isometric view thereof;

FIG. 3 is a front view thereof;

FIG. 4 is a rear view thereof;

FIG. 5 is a right side view thereof; the left side view is a mirror image of the right side view;

FIG. 6 is a top view thereof; and,

FIG. 7 is a bottom view thereof.
